UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

SECTIONAL PRINTING-FORM

1,054,284.

Specification of Letters Patent. Patented Feb. 25, 1913.

Application filed March 23, 1912. Serial No. 685,815.

To all whom it may concern:

Be it known that I, JOSEPH S. DUNCAN, a citizen of the United States, residing at Chicago, in the county of Cook and State of Illinois, have invented certain new and useful Improvements in Sectional Printing-Forms, of which the following is a specification.

This invention relates to printing forms in 10 general and more particularly to a sectional printing form adapted to print a full page letter or circular at one impression.

One of the primary objects of the present invention is the provision of a printing form 15 which shall be made up of a plurality of sheet metal form sections, each having printing characters struck up from one face thereof. The sections when assembled are arranged in juxtaposition upon a form bed 20 producing a composite form of the size required to print a single page.

Another object of the invention is to provide a suitable form bed to receive the form sections and retaining devices by means of 25 which the sections are secured to the bed and retained in the desired position thereon.

Other objects and advantages will be apparent to those skilled in the art as the invention is better understood by reference to 30 the following description when considered in connection with the accompanying drawings illustrating the invention in one of its preferred embodiments.

Referring to the drawings—Figure 1 is a 35 transverse sectional view of a printing form embodying my invention, this view being taken substantially on the line 1—1 of Fig 2; Fig. 2 is a plan view of a form section embodying my invention; and Fig. 3 is a fragmentary longitudinal section taken substantially on the line 3—3 of Fig. 2.

Various attempts to print letters in simulation of typewriting have been made prior 45 to my present invention but, so far as I am aware, the form from which the page is printed has not been made of sheet metal with the printing characters stamped up

therefrom. It is well known that printing characters stamped up from sheet metal will produce impressions very closely representing typewriting and, by means of the sheet metal printing form comprising the subject matter of the present application, a full letter page closely representing a typewritten page can be printed at one operation.

In order that the printing characters may be stamped up on the metal form without distorting the form or making it so large as to be unwieldy and difficult to operate upon, I prefer to make the form from a plurality 60 of sections which, when assembled, will produce an even and uniform printing surface. The sections are provided with a plurality of lines of printing characters by a graphotype or other suitable mechanism and when the 65 entire letter to be printed has been reproduced on a series of these printing sections the sections are assembled in juxtaposition on a form bed and are retained in position so that a uniform line spacing is secured 70 over the area of the form.

From an inspection of the drawings it will be observed that the form bed 5 which may be made of cast metal, or other preferred material, is provided on one face with a 75 series of transversely extending grooves or depressions 6 arranged in parallelism throughout the area of the bed. These grooves are spaced apart a distance equal to the width of the printing form sections 7 so 80 that when the sections are assembled on the bed their edges will abut against the adjacent sections.

The individual printing form sections, which form the subject matter of another 85 application filed concurrently herewith, are provided at one edge with downwardly extending flanges 8 which fit into the grooves 6 and prevent movement of the sections longitudinally of the bed. Each form section is 90 provided on its upper face with a plurality of lines of stamped up printing characters 9 and the sections are so constructed that when they are assembled on the bed the spacing

between the individual lines on the various sections will be equal to the spacing between the adjacent lines of abutting sections. A uniform line spacing over the area of the printing form is thereby secured.

For the purpose of locking the form sections to the bed I have provided suitable retaining devices which will now be described: Upon one side of the bed I provide 10 a retaining device in the form of a bar or plate 10 which extends slightly above the bed and is provided with an inwardly extending flange or lip 11 adapted to overlie the ends of the form sections. This device 15 is fixedly secured to the bed by suitable screws 12 or other preferred fastening means. The corner of the bed beneath the flange or lip 11 is preferably cut away as indicated at 18 so that the ends of the form section 7 may 20 be inserted under the flange without removing the retaining device 10 and when the sections are depressed flat against the face of the bed the ends will be tightly gripped beneath the flange. The top of the retaining 25 device 10 may be provided with a longitudinally extending groove 14, if desired, to provide means by which the temporary extensions on the printing sections may be broken off before they are positioned on the bed. A 30 second retaining device 15 is adjustably secured on the opposite side of the bed and also has at its upper edge an inwardly projecting lip or extension 16 adapted to overlie the ends of the printing sections at that side 35 of the bed. The retaining device 15 is adjustably secured to the bed 5 by screws 17 or other preferred fastening means and the perforations 18 through which the screws are inserted are made larger than the screws 40 and taper so that the tapered screw-head will draw the retaining device downwardly and firmly clamp the ends of the form sections between the bed and the overlying flange 16. The bed 5 is preferably provided with a 45 recess or rabbet 19 so that when the retaining device 15 has been removed one's fingers can be inserted beneath the projecting ends of the sections whereupon the sections may be readily removed from the bed.

50 From the foregoing it will be understood that the printing form is composed of a plurality of form sections each provided with lines of stamped up printing characters and arranged upon the bed to present a uniform printing surface comprising equally spaced lines of printing characters. The form sections when assembled on the bed are securely locked thereto in the desired position by suitable retaining devices and after the desired 55 number of printed copies have been obtained from the form the sections may be removed and replaced by other sections bearing the desired printing characters. It will thus be obvious that the bed and the retaining de-

vices may be used repeatedly with different 65 form sections while the individual sections may be filed away and used again, if desired.

It is believed that my invention and many of its attendant advantages will be understood from the foregoing without further 70 description and, while I have shown and described one preferred embodiment of the invention, it will be manifest that various adaptations of the broad conception may be resorted to without departing from the spirit 75 of the invention or sacrificing any of the material advantages thereof.

I claim:

1. A sectional printing form comprising a bed, a plurality of form sections arranged thereon and supported thereby between opposite edges of the sections, a retaining device fixed to one side of the bed and having a flange projecting over the bed, said bed being cut away below the flange and out to 85 the free edge thereof to permit the insertion of the ends of the form sections thereunder, and an adjustable retaining device at the opposite side of the bed whereby the form sections are clamped to the bed. 90

2. A printing device comprising a printing form, a bed supporting the printing form between its opposite edges, and a retaining flange carried by the bed and overlying one edge of the printing form, the 95 upper face of the bed being provided with a recess underlying the flange and extending to the free edge thereof, one edge of the recess and the free edge of the flange defining an entrance slot through which one edge of 100 the printing form may be introduced into the recess and beneath the flange.

3. A printing device comprising a bed having a beveled upper edge, a printing form lying upon the bed with one edge portion 105 overhanging the beveled portion of the bed, and a retaining device carried by the bed and provided with a retaining flange extending inwardly and overhanging the beveled portion of the bed and the adjacent edge of the printing form, the inner edge of the bevel and the inner edge of the flange defining an entrance slot through which one edge of the printing form may be introduced beneath the flange. 110

4. A printing device comprising a bed having one of its upper edges rabbeted, a printing form lying upon the bed with one edge overhanging the rabbeted portion of the bed, there being a space between the 120 overhanging edge portion of the printing form and the bottom of the rabbet to permit access to the overhanging printing form portion for removing the form and a removable retaining device carried by the rabbeted edge of the bed and provided with a flange overhanging the adjacent edge of the printing form. 125

5. A printing device comprising a bed having one of its upper edges beveled and its opposite edge rabbeted, a printing form resting upon the bed and overhanging the beveled and rabbeted portions thereof, a retaining device carried by the bed and overhanging the bevel thereof and the adjacent edge of the printing form, and another re- movable retaining device carried by the bed and overhanging the rabbeted portion there-¹⁰ of and the adjacent edge of the printing form.

JOSEPH S. DUNCAN.
